J. W. HAWKINS.
POCKET CLASP.
APPLICATION FILED NOV. 11, 1914.

1,173,349.

Patented Feb. 29, 1916.

Fig. 1.

Fig. 2.

A diagram of a tire tread pattern. The pattern consists of a series of sipes (grooves) in a zig-zagging, diagonal line. Eight points are marked along this line, labeled 1 through 8. Point 1 is at the top left, point 2 is at the top right, point 3 is in the middle left, point 4 is in the middle right, point 5 is at the bottom left, point 6 is at the bottom right, point 7 is in the middle left, and point 8 is in the middle right. The numbers are handwritten in black ink.

UNITED STATES PATENT OFFICE.

JOHN W. HAWKINS, OF MUNFORDVILLE, KENTUCKY.

POCKET-CLASP.

1,173,349.

Specification of Letters Patent.

Patented Feb. 29, 1916.

Application filed November 11, 1914. Serial No. 871,530.

To all whom it may concern:

Be it known that I, JOHN W. HAWKINS, a citizen of the United States, residing at Munfordville, in the county of Hart and 5 State of Kentucky, have invented a new and useful Pocket-Clasp, of which the following is a specification.

The device forming the subject matter of 10 this application is a clasp adapted to be applied to the pocket of a garment, to the end that a hand may be inserted into the pocket only with difficulty, thereby preventing an unauthorized removal of the contents of the pocket.

15 The present invention aims to provide a clasp of the type indicated which will conform to the contour of the wearer of the garment wherewith the device is assembled.

Another object of the invention is to provide 20 novel means for connecting the clasp to the pocket.

A further object of the invention is to improve the clasp structurally, notably in so 25 far as is concerned the relatively rigid strip and the means whereby the resilient grip is assembled with the strip.

With the above and other objects in view 30 which will appear as the description proceeds, the invention resides in the combination and arrangement of parts and in the details of construction hereinafter described and claimed, it being understood that changes in the precise embodiment of the invention herein disclosed can be made within 35 the scope of what is claimed without departing from the spirit of the invention.

In the accompanying drawings: Figure 1 40 shows in side elevation, a trousers pocket to which the clasp forming the subject matter of this application has been applied; Fig. 2 is an elevation showing the opposite side of the pocket and the clasp from that delineated in Fig. 1; Fig. 3 is a cross section on the line 3—3 of Fig. 1; Fig. 4 is a section on 45 the line 4—4 of Fig. 1.

In the drawings and referring particularly to Figs. 1, 2, 3 and 4, the numeral 1 indicates the pocket of a garment and in the present instance, a trousers pocket is shown. 50 To one side of the pocket 1 is applied a relatively rigid tubular strip 2. The strip 2 may be formed in any desired manner, but in the present instance, referring to Fig. 4, it will be seen that the strip is made by roll-

ing a sheet of metal upon itself, the resulting structure being flattened down to approximate an oblong cross section. Located within the strip 2 and extended longitudinally thereof near to the upper and lower edges of the strip are reinforcing elements 3 which preferably are made of metal. As indicated by the reference character 4 in Fig. 1, the ends of the reinforcing elements 3 protrude beyond the ends of the tubular strip 2 and, noting Fig. 2 and observing the point at which the reference character 5 is applied, it will be observed that the ends of the reinforcing elements 3 are bent over to form prongs 5 engaging the edges of the pocket 1 to hold the strip 2 in place thereon.

Assembled with the strip 2 is a grip, in the present instance shown in the form of a continuous elastic band 6. The band 6 passes through the strip 2 longitudinally, between the reinforcing elements 3 and lies along one of the outer faces of the strip. As will be understood readily, the strip engages one side of the pocket 1 and a portion of the band 6 engages the other side of the pocket, and thus the pocket is held closed. If desired, a strap 7 may extend transversely of the strip 2, the ends of the strap being attached to one side of the pocket 1. Another strap, indicated by the reference character 8 may be similarly mounted upon the other side of the pocket and may extend across the exposed, pocket-engaging portion of the resilient band 6.

As shown at 9 in Fig. 3, the strip 2 is concaved longitudinally upon one side and as a result is convexed longitudinally upon the opposite side. Since the strip is concaved as shown at 9, the same will conform to the cross sectional contour of the leg and the clothing will not be bulged owing to the presence of the strip 2. Since the strip 2 is convexed upon its outer side and since a portion of the band 6 extends longitudinally of the convexed side of the strip, the band will be tightened and remain thoroughly efficient as a pocket-engaging means, reference being had to Fig. 2.

From the foregoing it will be observed that there is shown in this application, a novel form of clasp which will close a pocket effectively, novel means being provided for assembling the resilient grip with the strip or body portion of the clasp, the body portion

of the clasp being of novel form, and novel means being provided whereby the entire structure is held upon the garment pocket.

Having thus described the invention, what is claimed is:—

5 A pocket clasp comprising a tubular strip; an endless elastic band constituting a grip extended through said tubular strip; spaced reinforcing elements in the strip; and 10 located on opposite sides of the grip, the ends of the reinforcing elements protruding

beyond the ends of the strip and being bent to form pocket engaging prongs, the prongs constituting means for maintaining the grip on the ends of the strip.

15 In testimony that I claim the foregoing as my own, I have hereto affixed my signature in the presence of two witnesses.

JOHN W. HAWKINS.
